UNITED STATES PATENT OFFICE.

JOHN C. NICHOLS, OF SHEBOYGAN, WISCONSIN.

HOPPLE COUPLING.

Application filed April 27, 1925. Serial No. 26,086.

This invention relates to hopple couplings.

In certain types of harness such, for instance, as hopples, the great stresses imposed at the joints of the sections of the hopple together with their continuous rocking motion even while the stresses are imposed, cause rapid wear to occur with consequent cutting through of the parts.

10 This invention is designed to overcome the above noted defects, and objects of the invention are to provide a hopple coupling which will transmit the severe stresses from one portion of the hopple to the other but which will prevent relative rocking motion of the adjacent parts and will thus avoid the rapid wear ordinarily occurring at these points.

An embodiment of the invention is shown 20 in the accompanying drawings, in which:—

Figure 1 is a fragmentary view of a hopple.

Figure 2 is a partial sectional view through the coupling and the adjacent portions of the hopple.

Figure 3 is a view of the coupling removed from the harness.

Figure 4 is a sectional view on the line 4—4 of Figure 1.

30 Although the coupling is eminently suited to hopple constructions, it nevertheless, may be used in other portions of the harness. However, for the purpose of illustrating the invention, a portion of the hopple is disclosed and is thought sufficient for illustrative purposes.

Referring to the drawings, it will be seen that a loop 1 of the hopple has been shown together with a portion of the intermediate strap 2. As is well known, suspending straps 3 and 4 are employed for holding the hopple in position.

The coupling is interposed between the straps 1, 2, and 4, as shown in Figure 1, and 45 firmly connects these portions and prevents relative rocking motion of the parts, thus avoiding the excessive wear formerly appearing at these points.

Referring to Figure 3, it will be seen that 50 the coupling comprises an upper and a lower bar 5 and 6, respectively, which are joined by an end bar 7 and an intermediate bar 8. A pair of bars 9 and 10 are arranged in laterally spaced and staggered relation adjacent the other end of the device and are adapted to receive the looped end 2' of the

strap 2, as shown most clearly in Figure 2, such loop passing around the intermediate bar 8. These spaced bars 9 and 10 prevent rocking of this intermediate portion of the strap.

The loop 1 is provided with a portion 1' which is passed around the end bar 7. This end bar, it will be noted, is provided with an outwardly projecting tongue 11 which extends between the portions of the strap 1. These portions of the strap are stitched together by upper and lower rows of stitching 12, as shown in Figure 1, thus definitely forming a pocket about the tongue 11 and holding such tongue rigid with reference to this portion of the strap.

The suspending strap 4 is passed around an upper bar 13 of the connector and forms a loop about such bar. This bar is provided with an upwardly projecting tongue 14 corresponding to the tongue 11, previously described. The folded portion of the suspending strap 4 is provided with spaced lines of stitching 15 which form a pocket for the reception of the tongue 14. The tongues 11 and 14 are of substantially similar construction. They are wider than their thickness and only a relatively slight bulge in the folded adjacent portions of the straps is occasioned by their presence. They occupy substantially the same relation to their respective straps and the sectional view shown in Figure 4, illustrates their relative position to the adjacent straps.

It will be seen that the members of the hopple cannot rock about the connector. The tongues 11 and 14 prevent such motion and consequently materially decrease the wear, and insure a longer life for the device even when subjected to great stresses.

When it is considered that the hopple has its parts positioned about the leg of the horse to restrict motion of the legs, it will be appreciated that the several members of the hopple are in violent motion and also are subjected to great stresses. This connector therefore, serves the highly useful purpose of forming an eminently effective coupling between the parts and also of preventing relative rocking motion of the parts with consequent wear.

It will be seen further that the device is extremely simple and may be very cheaply produced and easily positioned within the hopple.

Although the invention has been described

in considerable detail, it is to be understood that the invention may be variously embodied and is, therefore, to be limited only as claimed.

5 I claim:

1. A hopple including a strap adapted to be passed around a horse's leg, an intermediate connecting strap, and a suspending strap, a coupling member receiving the adjacent portions of the straps, and means on the coupling member cooperating with said straps to prevent relative rocking motion of the adjacent portions of said straps.
- 10 2. A harness coupling comprising a pair of

spaced members, an end bar joining one end 15 of such members and having an outwardly projecting prong, an intermediate crossbar, a pair of staggered cross bars joining said members adjacent their other end, and a bar carried by one of said members and a 20 spaced laterally therefrom and having an outwardly projecting prong.

In testimony that I claim the foregoing I have hereunto set my hand at Sheboygan in the county of Sheboygan and State of 25 Wisconsin.

JOHN C. NICHOLS.
